DIVIDED INDUCTOR WITH SURROUNDING
QUENCHING DEVICEJohn A. Evans, Milwaukee, Wis., assignor to Allis-
Chalmers Manufacturing Company, Milwaukee,
Wis., a corporation of Delaware

Application December 11, 1948, Serial No. 64,862

4 Claims. (Cl. 266—4)

1

This invention relates generally to improvements in means for inductively heating and for fluid quenching a workpiece and particularly to improved means for applying a quenching fluid through the work coil of an induction heater. And this invention is especially useful in connection with work coils having but one inductive turn or loop.

In the mass manufacture of machinery, it is common practice to machine many of the component parts from relatively soft stock; and then in a final operation to prepare these parts for surface hardening by feeding them into a work coil of a high-frequency induction heater. In surface hardening by induction heating followed by quenching, the steel is quickly raised to a bright-red heat by the induction heater, and then rapidly cooled by the quenching fluid. As a consequence, a relatively thin shell of hardened metal is produced surrounding the steel workpiece. The fact that the shell is thin is due to the skin effect always associated with the flow of high-frequency currents, and to the fact that the heat is applied so rapidly that the temperature can readily be confined to the surface layers.

In order to obtain the best grain structure for hardness, the temperature from which the workpiece is rapidly cooled should be above the critical temperature of the steel. Consequently it is important to quench the workpiece immediately following the heating operation. Otherwise the temperature of the heated shell may fall below the critical temperature before the quenching starts. Furthermore, any material flow of heat from the shell to the interior of the workpiece affects the final dimensions of the hardened surface layer. It is therefore the practice, when an induction heater is employed in assembly line manufacture, to feed into the work coil, one at a time, a series of workpieces for heating, and then at the end of the heating cycle, to rapidly quench each piece in place before removing it from the coil.

An examination of the prior art reveals that with some types of multturn work coils, the quenching liquid is introduced between adjacent turns of the coil, and with some types of single-turn work coils the quenching liquid is introduced from either side of the coil against the workpiece. In another type of single-turn coil, the quenching liquid is circulated through the coil, which is formed of copper tubing, and sprayed against the workpiece by means of a plurality of holes annularly spaced around the inside of the coil turn.

The disadvantages inherent in the prior art means for inductively heating and for quenching a workpiece are many, particularly with re-

2

spect to single-turn coils. In the type of single-turn coil first mentioned, in which the quenching liquid is directed against the workpiece from either side of the coil, the quenching is frequently localized and uneven, particularly if the coil is formed from a flat conductor having a width commensurate with the length of turn, since it is apparent that the liquid must first absorb heat from the end zones of the workpiece before reaching and absorbing heat from the central zone. If the liquid has a relatively long way to travel and changes to a gaseous state before reaching the central zone of the workpiece, the quenching action in that region is substantially nil. As a consequence, the workpiece may end up with a heat-treated zone not only of variable hardness but also of variable depth of hardness.

In the second type of single-turn coil mentioned above, in which the quenching liquid circulates through the hollow tubing of the coil, the duration of the applied heating cycle is definitely limited. This limitation is obvious when it is remembered that the energy transferred by the coil and the power absorbed in the coil are limited by the temperature rise, as in all electrical apparatus. In this type of coil, heat generated by the current flow is removed from the coil by the quenching fluid only in the period between heating cycles. During the heating cycle itself no cooling liquid flows through the coil.

In addition to the aforementioned disadvantages, the periodic application of quenching liquid to a work coil, whose temperature at the end of each heating cycle may be in the neighborhood of 250 to 500° F., will result in an initial flash of vapor at the beginning of each quenching cycle, providing the quenching liquid has a boiling point below the stated values. A time lag is thus introduced which begins at the end of the heating cycle and extends up to the instant when the quenching liquid portion still in the liquid state actually impinges on the workpiece. In this interval of time the temperature of the workpiece can fall below its critical temperature. As previously explained, the quenching of steel below its critical temperature adversely affects the final hardness. Since the degree of hardness achieved is also a function of the cooling rate it is important that the workpiece be quenched with a cold liquid rather than with a liquid that has previously been heated by passage through a hot work coil.

Furthermore, the periodic application of fluid adversely affects the work coil, since the flashing of the fluid to vapor causes the formation of scale in the interior of the coil, resulting in a decrease in the cooling channel cross section as well as in the cooling efficiency.

Still another drawback only too apparent is the inability of the coil in a brazing operation to dissipate sufficient heat when the coil is required to heat a workpiece having a resistivity comparable to that of the coil. If the workpiece is sufficiently heated during the heating cycle, the coil will be overheated, with a rapid formation of scale on the surfaces of the coil, both inside and out. Repeated heating operations under such conditions, if frequent enough, will eventually destroy the coil.

A satisfactory work coil for an induction heater embodies an inductor that will handle the maximum power output of the induction heater and still have as small a cross section as possible. With alloy steels containing large amounts of nickel, manganese, chromium and the like, the power requirements are likely to be high. Therefore, the inductor must be of small cross section to concentrate the power as much as possible. Furthermore, the inductor should be provided with a conduit capable of continuously circulating the requisite amounts of cooling fluid.

It is therefore an object of the invention to provide an improved heating inductor in which the aforementioned disadvantages of the prior art are obviated, and in which the aforementioned advantages are achieved.

The present invention proposes to cool the single-turn work coil of an induction heater by a continuous flow of cooling fluid and to apply the quenching fluid against the workpiece through the single-turn coil independently of the flow of cooling fluid.

Another object of the present invention is to provide an improved heating inductor in which the cooling fluid is circulated during energization of the inductor as well as during the application of quenching fluid to the workpiece.

Another object of the invention is to provide an improved heating inductor in which quenching fluid is directed through a turn of the inductor against the workpiece.

Another object of the invention is to provide an improved heating inductor in which quenching fluid is introduced through a turn of the inductor without the fluid impinging on the inductor prior to striking the workpiece.

Another object of the invention is to provide an improved heating inductor in which quenching fluid may be directed against the workpiece from substantially all sides of the inductor and through a turn of the inductor.

Another object of the invention is to provide an improved heating inductor which may be divided to insert a workpiece without interrupting the flow of cooling fluid.

Another object of the invention is to provide an improved heating inductor in which the source of quenching fluid is insulated from the inductor.

Another object of the invention is to provide an improved heating inductor in which the quenching and cooling fluids do not mingle.

Another object of the invention is to provide an improved heating inductor in which the quenching fluid is thermally insulated from heat generated by the inductor.

The novel features of this invention and how the objects are obtained will appear from the specification and the accompanying drawings showing several embodiments of the invention and forming part of this specification and all the novel features are intended to be pointed out in the claims.

In the drawings:

Fig. 1 is a plan view of an inductor and quenching jacket illustrating one embodiment of the invention in which part of the jacket is broken away to disclose the internal structure thereof;

Fig. 2 is a section taken through the inductor and quenching jacket of Fig. 1 along the line II-II thereof;

Fig. 3 is a section taken through the inductor and quenching jacket of Fig. 1 along the line III-III thereof;

Fig. 4 is a section taken through the quenching jacket of Fig. 1 along the line III-III thereof, the inductor being removed to disclose details of the quenching jacket;

Fig. 5 is a developed side view of the inductor of Fig. 1 together with part of the bus bar supports, the quenching jacket being removed to clearly define the inductor;

Fig. 6 is a plan view of a divided inductor and quenching jacket illustrating another embodiment of the invention;

Fig. 7 is a section taken through the divided inductor and quenching jacket of Fig. 6 along the line VII-VII thereof;

Fig. 8 is a detail section of a part of the divided inductor and quenching jacket of Fig. 6 taken along the line VIII-VIII thereof;

Fig. 9 is a developed diagrammatic view of a cooling tube forming part of the divided inductor shown in Fig. 6, together with a fragment of the bus bar support;

Fig. 10 is a diagrammatic section taken through a quenching jacket and inductor comprising another embodiment of the invention in which the quenching jacket and inductor are closely joined;

Fig. 11 is a developed view of a portion of an inductor only, part of the inductor being broken away to clearly disclose the structure thereof, illustrating still another embodiment of the invention.

As shown in Fig. 1, the induction heating apparatus comprises an inductive member or work coil 12 having a loop 13, the outer periphery of which is substantially enclosed by quenching means comprising a quenching jacket 14 of arcuate shape. The loop 13 of the work coil surrounds an opening 15 into which a workpiece, not shown, may be inserted for heating by induction. The coil 12 may be formed from electrically conductive tubing, preferably of silver or copper and of rectangular cross section. As shown in Figs. 3 and 5, the coil 12 comprises two single turns of tubing 17, 18 joined in electrical multiple parallel connection by means of a pair of bus bars, 19, 20, to form the single inductive loop 13. The single turns of tubing 17, 18 are arranged coaxially one above the other in general register and displaced axially to afford an arcuate slot or passage 22 between the turns through which quenching fluid may pass to reach the workpiece, not shown. In addition to providing the opening or passage 22 between the turns, the turns of tubing 17, 18 afford conduit passageways 23, 24, respectively, through which cooling fluid may flow independently of any flow of quenching fluid through the passage 22 defined by the turns.

The turn of tubing 17 has a pair of terminal end portions 25, 26 which extend in parallel relation for a short distance from the loop 13 of the coil 12 and then are bent in the same direction, as shown in Fig. 5, to extend substantially parallel to the axis of the coil. The turn of tubing 18 has a similar pair of terminal end por-

tions 27, 28. Electrical connection is made to the turns of tubing 17, 18 by means of the pair of bus bars 19, 20, respectively equipped with fingers 30, 31 inserted between the turns near the terminal portions thereof. Although, as shown in Fig. 3, the fingers 30, 31 extend to the opening 15 of the coil 12, they do not reduce the effective length of the slot 22.

The tubing turns 17, 18 are fastened to the fingers 30, 31 and to the adjacent portions of the bus bars 19, 20 by any suitable means, as by brazing. In this manner the coil 12 is supported in working position, and the turns 17, 18 of the coil 12 are supported in spaced relation to provide the arcuate slot or passage 22 with a uniform width of opening along its length. Furthermore, the connection of the turns 17, 18 to the bus bars 19, 20 in the manner described provides a rigid inductor having multiple parallel current paths and a single inductive turn, the parallel current paths being represented by the two single turns 17, 18.

The quenching jacket 14, surrounding the outer periphery of the coil 12 and spaced therefrom, comprises, as shown in Figs. 3 and 4, an arcuate outer wall 32 and an arcuate inner wall 33 in parallel curved relation, horseshoe-shaped top plate 34, and a horseshoe-shaped bottom plate 35, all joined together to define a conduit 36 for the flow of quenching fluid therethrough. Plates 38, 39 close the respective ends of the quenching jacket 14, the plates 38, 39 being fastened to the inner and outer walls 32, 33 in any suitable manner, as by screws 40.

The quenching jacket 14 is made from an insulating material, such as a suitable plastic. As shown in Fig. 4, the top plate 34 and bottom plate 35 are fastened to the walls 32, 33 by screws 41, but the fastening may be effected by any other suitable means.

The inner wall 33 of the quenching jacket 14 has a lesser width, measured in the direction of the axis of the coil 12, than the outer wall 32, which difference in width affords in the jacket 14 two arcuate passages 42, 43 through the inner wall 33, the one passage 42 being defined by the inner wall 33 and the top plate 34, and the passage 43 being defined by the inner wall 33 and the bottom plate 35. In addition to the two passages 42, 43, the inner wall 33 is centrally pierced by a third arcuate passage 44 which is similar in dimension to the two passages 42, 43 and disposed in general register radially with the arcuate passage 22 defined by the coil turns 17, 18. The two arcuate passages 42, 43 not only extend circumferentially around the inner wall 33 of the jacket 14 in axially spaced relation but also are disposed beyond the axial reaches of the coil 12. The dimensions of the one central passage 44 are less than the dimensions of the passage 22 defined by the coil turns 17, 18.

As shown in Fig. 1, the quenching jacket 14 is supported in spaced relation with the coil 12 by means of a pair of brackets 46, 47, respectively adapted to follow the outer contour of the bus bars 19, 20 and of the jacket 14. The brackets

46, 47 are shown respectively fastened to the bus bars 19, 20 by means of cap screws 48 threaded into the bars 19, 20. However, the fastening might be made by any other suitable means. Screws 50 engaging the outer wall 32 hold the brackets 46, 47 securely against the jacket 14.

Means for introducing quenching fluid into the quenching jacket 14 comprise circumferentially spaced openings 51 in the outer wall 32, into which are fitted couplings 52 for connection with a source of fluid, not shown. Similarly, cooling

fluid is introduced into the coil 12 through the respective terminal portions 25, 27 of the turns of tubing 17, 18 as shown in Fig. 5, the fluid flowing through each of the turns 17, 18 in the direction of the arrows, and emerging through the terminal portions 26, 28. If desired, terminal portions 26, 28 may be interconnected so that the cooling fluid will serially flow through the turns of tubing 17, 18.

In operation, the inductor or work coil 12 is connected to the current leads 54, 55 of an induction heater, not shown, the connection being effected by bolting the bus bars 19, 20 respectively to the current leads 54, 55.

A workpiece, not shown, is inserted in the opening 15 of the work coil 12 and the coil 12 energized by passing through it a high frequency current. An alternating magnetic flux is thereby generated in the work coil 12, which flux links the workpiece and by means of induced currents rapidly raises the temperature of the workpiece. During the period the coil 12 is energized, cooling liquid is continuously circulated through the turns of tubing 17, 18 in order to limit the temperature rise of the coil 12.

When the workpiece has reached its critical temperature, the coil 12 is deenergized and quenching fluid under pressure is introduced into the quenching jacket 14 by way of the couplings

52. The quenching fluid is forcibly ejected through the passages 42, 43 in the wall 33 and passes over the axial reaches of the coil 12 into the opening 15 where it impinges on the workpiece. Quenching fluid ejected from the central passage 44 passes through the passage 22 defined by the coil turns 17, 18 before reaching the workpiece. The three passages 42, 43 and 44 in the quenching jacket are so dimensioned and arranged with respect to the coil 12 and the passage 22 therein that the substantially laminar flow of quenching fluid from the jacket 14 enters the opening 15 of the coil 12 without impinging on any portion of the coil structure during its passage through the coil 12. In short, the coil 12 offers no impediment to the flow of quenching fluid, the fluid flows freely from the quenching jacket 14 into the opening 15 of the coil 12 against the workpiece.

It is unnecessary to interrupt the flow of cooling fluid either during the heating cycle or during the quenching cycle, inasmuch as the flow of cooling fluid is independent of the flow of quenching fluid and the flow of current through the coil 12.

The temperature of the quenching fluid as it emerges from the jacket 14 is not effected by the power absorbed in the coil 12, since the cooling fluid passing through the coil 12 takes up the resulting heat. By spacing the jacket 14 from the coil 12 to afford a cylindrical layer of air therebetween and by providing a relatively thick inner wall 33 for the jacket 14, the quenching fluid is further insulated thermally from the coil 12.

In the alternative embodiment shown in Fig. 10, the quenching jacket 57 abuts the inductor member 58 so as to leave no intervening space between the walls of the jacket 57 and the walls of the inductor member 58. Portions of the walls of the tubal segments 59, 60 of the inductor member form the discharge passage 61 through which the quenching fluid flows to meet the workpiece, not shown. In this construction the passage 61 actually guides the flow of fluid in its passage through the inductor member 58.

In the further alternative embodiment shown in Fig. 11, the inductor member 63 comprises an inner wall 64, an outer wall 65, a top side wall 66, and a bottom side wall 67 defining therebetween a passageway 68 for the flow of cooling fluid, and a transverse wall 69 extending between the side walls 66, 67, the transverse wall defining a passage 70 connecting the outer wall 65 with the inner wall 64 for the passage of quenching fluid therethrough.

Thus the work coil 12, of Fig. 1, can be constructed in the manner shown in the embodiments of Figs. 10 and 11 without departing from the spirit of the invention.

In the apparatus above described, the workpiece to be heated is inserted into the coil opening 15 either from above or below the coil 12. The coil opening 15 is limited to workpieces having configurations commensurate with the size of the opening, since the coil 12 is not itself separable. In order to heat any portion of a workpiece which has a configuration incommensurate with the size of the coil opening 15, such as a crankshaft or the like, an alternative embodiment of the invention, as shown in Fig. 6, is utilized, in which the heating apparatus is separable into two portions which can be clamped around any section of a workpiece commensurate with the coil opening, as for example, the bearing surface of a crankshaft.

The heating apparatus shown in Fig. 6 comprises a supporting bracket 12, on which is mounted an inductor or work coil 73 together with quenching means hereinafter described, the coil 73 and quenching means being divided into two similarly constructed conductive assemblies 75a, 75b capable of being separated for the purpose of inserting a workpiece, not shown, into the opening 76 in the loop of the coil 73. The conductive assembly 75a comprises an inductor half or inductor segment 77a, and quenching means comprising a quenching jacket 78a. The conductive assembly 75b similarly comprises an inductor segment 77b and quenching jacket 78b. The work coil 73 is here shown in the working position, in which the two inductor segments 77a, 77b engage to form a single inductive loop for the passage of alternating current therethrough. Since the conductive assemblies 75a, 75b are substantially bilaterally symmetrical with the exception of the clamping means hereinafter described, the following description of one conductive assembly 75a will suffice to delineate the other conductive assembly 75b, like parts in the two assemblies being indicated by the same reference character followed by an identifying suffix *a* or *b*.

The conductive assembly 75a comprises an insulating block 79a in which a bus bar 80a for supplying current to the inductor segment 77a is partially imbedded. As shown in Fig. 7, the segment 77a is carried by one end of the bus bar 80a which is of substantially rectangular cross section, and the bus bar 80a is hingedly supported at its other end by means of a hinge pin or bolt 82a extending through the bracket 12. Provision is made for leading current to the bus bar 80a through a conductor 83a having a terminal portion 84a hingedly connected to the bus bar 80a between a bifurcated end portion 85a thereof. In order to insure a good electrical connection between the bus bar 80a and the conductor 83a, and further, in order to impart mechanical rigidity to the conductive assembly 75a, the block 79a is also provided with a bifurcated hinge

portion 86a closely fitting over and abutting the bifurcated portion 85a of the bus bar 80a and held for movement therewith by clamping means comprising the bracket 72 and a nut 87a threaded to the hinge bolt 82a.

As shown in Fig. 6, the conductive assembly 75a is capable of being swung, in a clockwise direction about the bolt 82a as a center, from the working position shown to an open or non-working position. In a similar manner the other conductive assembly 75b can be swung about the bolt 82b in a counterclockwise direction from the working position to the open position. Stops 88a, 88b are respectively provided for each of the conductive assemblies 75a, 75b so that the inductor segments 77a, 77b can engage in proper alignment to form a conductive loop upon swinging the conductive assemblies 75a, 75b to the working position. The two stops 88a, 88b are similar, the stop 88a comprising a projection on the bus bar 80a at the hinged portion 85a thereof adapted to engage a projecting pin 89a mounted on the bracket 72.

The inductor segment 77a carried by the bus bar 80a is formed from electrically conductive tubing, preferably of silver or copper and of rectangular cross section. The tubing, as best shown in the developed view of Fig. 9, comprises a plurality of arcuate portions 91a, 92a, 93a, and 94a, spaced in general register one from the other, and joined in a mechanical series connection through mitered tubular sections 95a, 96a, and 97a inserted respectively between adjoining ends of the tube portions 91a, 92a, 93a, and 94a at right angles thereto. The tubing might have been bent from a single piece into a configuration approximating that of Fig. 9, but such a method of construction would not have resulted in the sharply defined corners made possible by jointly mitering the ends of the tube portions 91a, 92a, 93a, and 94a and the interconnecting sections 95a, 96a, and 97a. When connected as shown in Fig. 9, the tube portions 91a, 92a, 93a, and 94a provide a conduit for the flow of cooling fluid therethrough, the direction of flow being indicated by the arrows.

The outer tube portions 91a, 94a of the inductor segment 77a are considerably longer than the intermediate tube portions 92a, 93a and are carried back along one side of the bus bar 80a, as shown in Figs. 7 and 8, to the region of the hinge connection, where the tube portions 91a, 94a are suddenly bent to extend in parallel at right angles to the bus bar, as best seen in Fig. 6. That part of each tube portion 91a, 94a lying along the bus bar 80a is secured thereto by brazing or the like.

Similarly, the interconnecting tube section 95a is brazed to the tip of the bus bar 80a, thus insuring, together with the brazed portions of tubing 91a, 94a, a strong support for the inductor segment 77a.

A contact 101a, preferably of silver and having a rectangular shape, is placed across the end 65 of the segment 77a comprising the interconnecting tubing sections 96a, 97a, and securely fastened thereto, as by brazing the contact 101a, to the sections 96a, 97a. With contact 101a in place, the segment 77a comprises a plurality of parallel current paths represented by the tube portions 91a, 92a, 93a, and 94a. Furthermore, the tube portions 91a, 92a, 93a, and 94a, together with the sections 95a, 96a, 97a and the contact 101a, 70 now define a plurality of arcuate slots or passages

102a, 103a, and 104a leading through the segment 77a.

As shown in Fig. 6, the contact 101a extends radially of the coil 73 into the passage between the conductive assemblies 75a, 75b. In this position the contact 101a abuts a portion of the plate 109a. Similarly the contact 101b extends into the passage between the conductive assemblies 75a, 75b and abuts a portion of the plate 109b. Upon moving the assemblies 75a, 75b into the working position shown in Fig. 6, the contacts 101a, 101b are urged into conductive engagement by the pressures respectively exerted by the plates 109a, 109b. In this way, a positive electrical connection between the contacting surfaces of the inductor segments 77a, 77b is insured when the conductive assemblies 75a, 75b are locked in the working position, as hereinafter described.

The quenching jacket 78a, a portion of which surrounds the outer periphery of the inductor segment 77a and is spaced therefrom, comprises, as shown in Fig. 6, a portion of the block 79a having a bight 105a therein conforming substantially to the contour of the outer periphery of the inductor segment 77a. An arcuate channel 106a for the flow of quenching fluid is so cut in the block 79a adjacent the bight 105a as to leave an inner wall 107a in the block facing the segment 77a. Plates 108a, 109a respectively close off the ends of the arcuate channel 106a.

A longitudinally-extending riser channel 111a is cut in the block 79a adjacent to the arcuate channel 106a and connected therewith by means of a plurality of radially extending channels 112a. One end of the riser channel 111a is closed by a plug 113a. The other end of the riser channel 111a communicates with an opening 114a in the block 79a. The opening 114a provides means, indicated in part by a fragment of a pipe nipple 113a, for introducing quenching fluid into the block 79a from a source, not shown.

A cover plate 117a and a bottom plate 118a of insulating material and having, respectively, edge contours conforming to the edge contour of the bight 105a are attached in fluid tight relation to the jacket portion 78a of the block 79a by any suitable means, as by the use of a suitable adhesive or thermosetting plastic, the plates 117a, 118a providing top and bottom walls for the channel 106a.

As shown in Fig. 7, the inner wall 107a of the block surrounding the inductor segment 77a is pierced by a plurality of arcuate parallelly disposed passages 119a, 120a, and 121a through which the arcuate channel 106a can discharge quenching fluid into the region of the bight 105a. The passages 119a, 120a, and 121a are so constructed and arranged as to be respectively in general register with the corresponding passages 102a, 103a, and 104a through the inductor segment 77a. The dimensions of the passages 102a, 103a, and 104a in the inductor segment 77a are greater than the dimensions of the passages 119a, 120a and 121a through the block wall 107a so that the substantially laminar flow of quenching fluid ejected through the passages 119a, 120a, and 121a of the block 79a will pass through the inductor segment 77a without impinging on any portion thereof.

Means is provided for clamping the two conductive assemblies 75a, 75b in conductive engagement when the assemblies have been swung to the working position, as shown in Fig. 6. The clamping means comprises a bail 123 pivotally mounted on an extension 124 of the conductive

assembly 75b, the bail having a resiliently-supported transverse member 125 adapted to engage an extension of the other conductive assembly 75a when the bail 123 is swung into the clamping position shown. An operating handle 126 integral with the bail 123 is provided for swinging the bail 123 into and out of the clamping position. Means for locking the bail 123 in an open position when the conductive assemblies 75a, 75b have been separated is provided. The locking means comprises a pin 127 pivotally mounted on extension 124 of the conductive assembly 75b, the pin 127 having a detent 129 adapted to intercept a lug 130 on the handle 126 when the pin 127 is biased counterclockwise as far as it will go, as for example, when the conductive assembly 75b has been swung into the open position.

When the conductive assembly 75b is swung into the closed or working position, as shown in Fig. 6, the pin 127 is rotated clockwise to the indicated position, permitting the bail 123 to be freely swung into the clamping position. Upon locking the bail 123 in the open position, the detent 129 holds the handle 126 in an extended position whereby the handle 126 can be used for swinging the conductive assembly 75b about its pivotal bolt 82b.

How the work coil 73 operates to inductively heat and to quench a workpiece will appear from the following description of such an operation.

Starting with the work coil 73 in the closed position shown in Fig. 6, the operating handle 126 is swung in a counterclockwise direction unclamping the conductive assemblies 75a, 75b, whereupon the conductive assembly 75b is swung to the open position. If more space is required for inserting a workpiece between the two conductive assemblies 75a, 75b, the other conductive assembly 75a can also swing into the open position. A workpiece, not shown, is then centrally positioned between the conductive assemblies 75a, 75b so that upon closing and clamping the conductive assemblies 75a, 75b the workpiece has the section thereof which is to be heat treated enclosed by the loop of the work coil 73.

After the conductive assemblies 75a, 75b are clamped in working position with the inductor segments 77a, 77b electrically engaged to form a conductive loop, the work coil 73 is energized, thereby heating the work piece. The current flow is through the conductor 83a, the bus bar 80a, the multiple parallel paths provided by the segment 77a, and similarly through the other segment 77b, the bus bar 80b, and the conductor 83b.

When the workpiece has reached its critical temperature, the work coil 73 is instantly deenergized and quenching fluid under pressure is immediately introduced into the blocks 79a, 79b to be ejected against the workpiece through the respective passages of the conductive assemblies 75a, 75b. Thus quenching fluid flows through the quenching jacket 78a as follows: Fluid introduced into the quenching jacket 78a via the pipe nipple 115a flows into the riser channel 111a where it is diverted into the radially extending channels 112a. From the channels 112a the fluid flows into the arcuate channel 106a from which it is forcibly ejected through the arcuate slots or passages 119a, 120a, and 121a. In a similar manner, the quenching fluid flows through the quenching jacket 78b.

Following the quenching of the workpiece the operating handle 126 is swung to unclamp the conductive assemblies 75a, 75b which are then

swung about their respective pivots 82a, 82b to the open position. The workpiece is then removed; a new workpiece is inserted and the cycle of operations just described is repeated.

During the heating and quenching periods, and during the period in which the conductive assemblies 75a, 75b are in the open position, cooling fluid may be continuously circulated through the tubing without interfering in any way with the described operation. The provision of separate tubing for the flow of cooling fluid in each coil assembly makes possible this continuous circulation of cooling fluid. There is no mingling of the cooling fluid with the quenching fluid. The flow of each is entirely independent of the other.

Although several embodiments of the present invention have been herein illustrated and described, and although these embodiments have been described particularly in connection with single-turn inductors, it will be apparent to one skilled in the art that the invention may have desirable functional utility in multiple-turn inductors, i. e., inductors having more than one inductive turn in series connection. And it should be understood that the invention of the appended claims is not limited to the exact details of design and construction described herein, for obvious changes and modifications within the scope of the claims will be apparent to those skilled in the art.

It is claimed and desired to secure by Letters Patent:

1. Means for inductively heating and for quenching a workpiece comprising: a dividable inductor comprising a plurality of conductive assemblies; means for supporting said assemblies in mutually conductive engagement; each of said assemblies comprising a conductive arcuate segment and fluid quenching means associated in insulated and spaced relation with said segment, said segment comprising a tube for the continuous flow of cooling fluid therethrough, said tube comprising an array of adjacent parallel arcuate portions in general register and means for connecting said tube portions in hydraulical series connection, and means for connecting said tube portions in electrical parallel connection, said electrical connecting means cooperating with adjacent said tube portions to define at least one arcuate slot between said adjacent tube portions; said quenching means comprising a conduit for providing a source of quenching fluid under pressure, said conduit comprising an arcuate wall portion facing said segment, said wall portion defining at least one arcuate fluid passage having a transverse width less than the transverse width of said slot in said segment, said one passage being in general register with said one slot for forming and directing a sheet of quenching fluid freely through said one slot whereby said quenching fluid passes freely between said tube portions.

2. Means for inductively heating and for quenching a workpiece comprising: a dividable inductor comprising a plurality of conductive assemblies; means for supporting said assemblies in mutually conductive engagement; each of said assemblies comprising a conductive segment and fluid quenching means associated with said segment, said segment comprising a tube for the continuous flow of cooling fluid therethrough, said tube comprising an array of adjacent parallel portions and means for connecting said tube portions in hydraulical series connection; and means for connecting said tube portions in elec-

trical parallel connection, said electrical connecting means cooperating with adjacent said tube portions to define at least one opening between said adjacent tube portions; said quenching means comprising a conduit for providing a source of quenching fluid under pressure, said conduit comprising a wall portion facing said segment, said wall portion defining at least one fluid passage in general register with said one opening for forming and directing a stream of quenching fluid freely through said one opening whereby said quenching fluid passes freely between said tube portions.

3. Means for inductively heating and for quenching a workpiece comprising: a dividable inductor including a tube for the flow of cooling fluid therethrough, said tube comprising adjacent parallel portions and means for connecting said tube portions in hydraulical series connection; means for connecting said tube portions in electrical parallel connection, said electrical connecting means cooperating with adjacent said tube portions to define at least one opening between said adjacent tube portions; and fluid quenching means associated with said inductor, said quenching means comprising a conduit for providing a source of quenching fluid under pressure, said conduit comprising a wall portion facing said inductor, said wall portion defining at least one fluid passage in general register with said one opening for forming and directing a stream of quenching fluid freely through said one opening whereby said quenching fluid passes freely between said tube portions.

4. Means for inductively heating and quenching a workpiece comprising: a dividable inductor including a tube for the flow of cooling fluid therethrough, said tube comprising adjacent parallel portions and means for connecting said tube portions in hydraulical series connection; means for connecting said tube portions in electrical parallel connection, said electrical connecting means cooperating with said tube portions to define a plurality of openings between said tube portions; and fluid quenching means associated with said inductor, said quenching means comprising a conduit for providing a source of quenching fluid under pressure, said conduit comprising a wall portion facing said inductor; said wall portion defining a plurality of fluid passages, each of said passages being in general register with a respective one of said openings for forming and directing a stream of quenching fluid freely through said one of said openings, whereby said quenching fluid passes freely between said tube portions.
